UNITED STATES PATENT OFFICE.

JOHN S. JACKSON, OF CLINTON, ILLINOIS, ASSIGNOR OF ONE-HALF TO FREDERICK BALL AND W. D. BARNETT.

RAIL JOINT AND CHAIR.

1,129,098.

Specification of Letters Patent. Patented Feb. 23, 1915.

Application filed May 25, 1914. Serial No. 840,792.

To all whom it may concern:

Be it known that I, JOHN S. JACKSON, a citizen of the United States, residing at Clinton, in the county of DeWitt and State 5 of Illinois, have invented certain new and useful Improvements in Rail Joints and Chairs; and I do declare the following to be a full, clear, and exact description of the invention, such as will enable others skilled in 10 the art to which it appertains to make and use the same.

My invention relates to improvements in railway chairs and joints and has for its object to provide a simple, efficient and inexpensive device of this character which will obviate the necessity of employing bolts, nuts, and nut locks for uniting the meeting ends of the rails.

To the above end, I employ a rectangular 20 base block, rail bracing plates carried thereby, said plates acting also to prevent the removal of a number of fastening pins to be described.

A secondary object of the invention is to 25 provide simple and efficient means for securely locking said bracing plates in position.

With the above and other minor objects 30 in view, the invention resides in certain novel features of construction and combination herein described and claimed and shown in the drawings wherein:

Figure 1 is a top plan view of the invention showing the manner of its application; 35 Fig. 2 is a side view of the parts shown in Fig. 1; Fig. 3 is a vertical section through one of the rails, showing an end elevation of the joint; Fig. 4 is a vertical transverse section on the line 4—4 of Fig. 1; Fig. 5 is a 40 perspective view of one of the bracing plates; Fig. 6 is a similar view of one of the members, employed for retaining said plates in position; and Fig. 7 is a perspective view of the entire base block.

In the accompanying drawings, I have 45 shown the meeting ends of two rails R, the webs of said rails being provided with the usual transverse openings O. Disposed between the flanges F of said rails and the 50 cross ties T is my improved chair and coupling.

The invention comprises a base block 1 which extends longitudinally of the rails R and is preferably rectangular at its base, its 55 opposite ends 2 rising vertically, while its

longitudinal side walls 3 incline upwardly and inwardly. The block 1 is provided, at the juncture of the inclined walls 3, with an inverted T-shaped slot 4 which opens through its upper side, said slot being provided for the reception of the flanges F of the rails R and for the lowermost portions of the webs W thereof, the upper edges of said walls being provided with transverse notches 5 which, when the rails are in position, align with the openings O. When in this position, pins 6 are passed through said aligned notches and openings, said pins having their upper portions beveled as at 7 in order to cause their ends to lie flush with the 70 inclined walls 3.

For the purpose of more rigidly bracing the rails R and for retaining the pins 6 in position, I provide a pair of longitudinal bracing plates 8 which are substantially 75 wedge-shaped in cross section and having their upper edges held in forcible contact with the under sides of the heads H of the rails R by means of longitudinal ribs 9, the latter being cast integrally with the side 80 walls 3 and having their inner edges undercut as shown at 10, said under-cut portions co-acting with the narrow lower edges of said bracing plates.

On the inside of the track, the bracing plate 8 is preferably held in proper position by means of a pair of spikes 11 which pass through notches 12 in the lower edge of said clamping plate and are driven through suitable openings through the block 1 and into certain of the cross ties T. As clearly shown in Fig. 1, the ribs 9 terminate a slight distance from the ends of said block 1 for allowing the proper application of the spikes 11 on the inside of the track and for allowing ample space for the provision of other fastening means which are employed on the outside of the track. Said last mentioned means comprises inclined plates 13 which are suitably shaped, on their under sides for contact throughout their length with the inclined walls 3 and the outer faces of the bracing plates 8, the inner edges of said plates contacting with the ends of the ribs 9, while the outer edges thereof are provided with upright plates 14 which extend laterally therefrom and contact with the ends of the bracing plates 8 and with the ends 2 of the base block 1. The plates 13 are preferably secured in this position by spikes 15. 100 105 110

which pass through alined openings in said plates and the base block 1 and enter certain of the ties T.

When it becomes necessary to remove the 5 rails, the spikes 11 and 15 are removed, whereupon the plates 13 and the bracing plates 8 may be readily removed, thereby allowing said rails to be pulled endwise out of the slots 4, after the pins 6 have been 10 removed.

From the foregoing description, taken in connection with the accompanying drawings, it will be seen that I have produced a comparatively simple, yet extremely efficient 15 rail chair and joint, the construction and operation of which will be readily understood without requiring a more extended explanation.

Although I have described my invention 20 with considerable minuteness, I do not wish to be limited to details of construction, other than those amplified in the appended claims.

Having thus described my invention, what 25 I claim as new and desire to secure by Letters-Patent is:

1. The combination with the meeting ends of a pair of rails having openings through their webs, of a one-piece base block having an inverted T-shaped slot extending longitudinally throughout its upper portion and adapted for the reception of the base flanges and webs of the rails, the material to each side of said slot being provided with notches alined with the openings in said rails, pins 30 passing through said alined notches and openings, undercut longitudinal ribs on said base block and longitudinal bracing and pin retaining plates between said undercut ribs and the under sides of the heads of the rails.

40 2. The combination with the meeting ends of a pair of rails having openings through their webs, of a one-piece base block having a longitudinal rectangular base and upwardly and inwardly inclining side walls, 45 said block having a longitudinal inverted T-shaped slot at the juncture of said side walls for the reception of the base flanges and webs of the rails, the upper edges of said walls having notches alined with the openings in said rails and opening into said slot, transverse pins in said alined openings and notches, longitudinal undercut ribs on said side walls of the base blocks, and longitudinal rail bracing and pin retaining plates 50 forcibly contacting with the under sides of the heads of the rails and with the undercut portions of said ribs.

3. The combination with the meeting ends

of a pair of rails having openings through their webs, of a one-piece base block having 60 a longitudinal rectangular base and upwardly and inwardly inclining side walls, said block having a longitudinal inverted T-shaped slot at the juncture of said side walls for the reception of the base flanges 65 and webs of the rails, the upper edges of said walls having notches alined with the openings in said rails and opening into said slot, transverse pins in said alined openings and notches, longitudinal undercut ribs on 70 said side walls of the base block, said ribs terminating at points spaced from the ends of the block, longitudinal rail bracing and pin retaining plates forcibly contacting with the under sides of the heads of the rails and 75 with said undercut portions, said plates terminating even with the ends of the block, inclined plates overlying said inclined walls of the base block and contacting with the ends of said ribs, and upright portions extending laterally from said inclined portions and contacting with the ends of said block and the ends of said bracing plate and fastening elements passing through said inclined plates and said base block and 80 adapted to enter the cross ties.

4. The combination with a base block having a rail seat, a shoulder spaced laterally therefrom and a rail bracing and clamping plate between said shoulder and the rail and terminating flush with one end of the block, of an angular end plate in contact with the contiguous ends of said bracing plate and said base block for preventing removal of the former.

5. The combination with a base block having a rail seat, a shoulder spaced laterally therefrom and a rail bracing and clamping plate between said shoulder and the rail and terminating flush with the ends of the block, 90 of end plates overlying the end portions of said block and bracing plate, laterally extending portions on said end plates and in contact with the extreme ends of said block and said bracing plate and fastening elements passing through said end plates and said base block and adapted to enter the 95 cross ties.

In testimony whereof I have hereunto set my hand in presence of two subscribing witnesses.

JOHN S. JACKSON.
